UNITED STATES PATENT OFFICE

JOHN N. WHITEHOUSE, OF NEW YORK, N. Y.

DESIGN FOR A FOUNTAIN PEN OR SIMILAR ARTICLE

Application filed April 23, 1932. Serial No. 43,584. Term of patent 7 years.

To all whom it may concern:

Be it known that I, JOHN N. WHITEHOUSE, a citizen of the United States of America, and resident of New York, in the county of New York, State of New York, have invented a certain new, original, and ornamental Design for a Fountain Pen or Similar Article, of which the following is a specification, reference being had to the accompanying drawing, forming part thereof.

In the drawing:

The figure is a side elevation of a fountain pen or similar article showing my new design. The novelty of the design resides in the ornamental effect resulting from the staggering of the surface panels of the article near the end of the barrel thereof and near the end of the cap thereof.

I claim:

The ornamental design for a fountain pen or similar article substantially as shown and described.

JOHN N. WHITEHOUSE.
